UNITED STATES PATENT OFFICE.

ELI A. D. REYNOLDS, OF APPLETON, WISCONSIN.

PULP-DIGESTER.

SPECIFICATION forming part of Letters Patent No. 423,531, dated March 18, 1890.

Application filed June 18, 1888. Serial No. 276,945. (No model.)

To all whom it may concern:

Be it known that I, ELI A. D. REYNOLDS, of Appleton, in the county of Outagamie and State of Wisconsin, have invented certain new and useful Improvements in Pulp-Digesters; and I do hereby declare the following to be a full, clear, and exact description of the invention, such as will enable others skilled in the art to which it appertains to make and use the same.

My invention relates to digesters used to disintegrate the fibrous tissues of wood and render it a flocculent mass by a complete separation of its filaments, the operation being conducted in a closed chamber, into which the chips or fragments of wood are introduced, along with a solution of sulphurous acid, and therein boiled, this being technically known as the "bisulphite process." It is well known to those conversant with the art that the strong solution of sulphurous acid employed to reduce the wood to a pulp by decomposition of albuminous matter contained in its cellular tissues has a very destructive effect upon the metallic shell of the boiler, which to insure requisite strength is usually made of iron or steel plate. When a charge of wood and acidulous liquid is being manipulated within the digester-shell, if proper means are not employed to prevent direct contact of the acid with the shell a chemical action results and the iron or steel is decomposed, producing a dark-colored residuum, which when incorporated with the charge of pulp will badly color it and render it unfit for manufacture of white or tinted paper.

To overcome the evil results of chemical decomposition just named numerous devices have been employed with varying results. Experience indicates that the best lining for a pulp-digester shell is porcelain-coated brick, commercially known as "glazed tile," they having enameled or vitreous facing which is unaffected by acid solutions. To render the porcelain-faced tile available for use as a lining for pulp-digesters, it is necessary to provide a reliable means for securing them in place, and also of affording perfectly acid-proof joints between the brick when placed to form an inner shell for the digester-chamber. It is also important that there should

be a proper backing or cushion interposed between the wall or brick and the metal shell of the digester-chamber to permit a limited expansion of the brick and shell when heated. 55

One object of my invention is to provide a means for utilizing either asbestos, lead, or their equivalent as a joint between the tiles and hold the joint material in place.

Another object of my invention is to construct the tile in such a manner as to form an interlocking face on continuous rows of tile, and thus render the wall secure when erected in place.

A further object is to provide an acid-proof joint interposed between the several rows of peculiarly-constructed tile, as additional means to prevent escape of acid solutions from the interior chamber toward the metal shell.

A further object is to furnish a pulp-digester with a gaseous or fluid packing—as air, steam, or water—that is interposed between the inner surface of the metal shell and the adjacent surface of an improved construction of tile-lining wall, so as to permit expansion 70 and overcome any excess of expansion of the iron shell or that of the brick wall and maintain a pressure sufficient to hold the brick intact, and if water is used to dilute any acid which might enter this water-space rendering 75 it inert, and thus prevent corrosion of the metal shell of the digester.

A further object is to furnish a digester-shell having a lining separated therefrom, so as to form a fluid-chamber between their adjacent surfaces with a coating, which will protect it from acid solutions or rust due to water or steam that would have contact therewith if not so protected, a plastic composition coated upon the interior surface of the shell 85 being the preferred way of protecting the shell.

With these objects in view my invention consists in certain features of construction and combinations and arrangements of parts, 95 which will be hereinafter described, and pointed out in the claims.

Referring to the drawings making a part of this specification, Figure 1 is a side elevation, in section, of a digester-chamber with the tile in position therein. Fig. 2 represents an enlarged perspective view of several wall-

tiles detached. Fig. 3 is a detached sectional elevation of several of the tiles composing the lining-wall of the digester-chamber.

A represents the metal shell of the digester, which is preferably made cylindrical in form, stationary, and in an upright position, but by an obvious modification of form the digester may be made to rotate on trunnions, if desired.

The shell A, constructed of steel or iron plate, is preferably slightly inclined from the center toward the circumference on the lower surface and provided with a suitable outlet M, through which the contents may be discharged, the upper end being arched and provided with a man-hole covered by a plate E, held in place by a clamp E' and bolt E², in the usual manner employed to seal such orifices.

Within the shell A a wall of glazed tiles C is erected of such a proportionate diameter with regard to the shell A that there will be an annular space B between the wall and shell, said space being intended to receive a gaseous or fluid matter, as water, steam, or compressed air, preference being given to water as a filling for the space B.

The bricks or tiles C that compose the lining-wall of the digester are made of proper form to joint together and have their opposite faces conform, so that a comparatively thin asbestos or lead joint G may be introduced between the tiles to form acid-proof joints between them.

By inspection of Fig. 3 it will be seen that the bricks or tiles C are provided with projecting tongues c and mating grooves C', which are adapted to interlock when the bricks are jointed together. These interlocked projections and corresponding channels are formed on the bricks at any preferred point on their surfaces between the concave inner vertical faces a and the convex faces b, which latter form the surface of the tile wall adjacent to the metal shell A.

Referring to Figs. 2 and 3, it will be seen that the tongues c are made as square-cornered projections from the vertical jointing-faces of the tiles C, and the grooves, which are cut at proper points on the adjacent tiles, are adapted to conform to the tongues, so that the asbestos or sheet-metal joints G may be introduced between the tongue-and-groove formations to produce a continuous joint from the inner concave face of each adjacent pair of tiles to their convex surface, which is adjacent to the metal shell A, it being understood that there are vertical joints between each upright row of the tiles. There is also a tongue-and-socket interlock of the horizontal faces of successive tiers or rows of the tiles, as shown in Figs. 2 and 3, and consist of recesses or open socket-holes i, made in the faces on one side of the row of tiles, and tongues i', formed integral upon the adjoining row, that are in proper relative position to enter the sockets. It will be noticed that the tongues i' are one-half the width of a receiving-socket, so that

two tongues formed on an adjacent pair of tiles will together enter one socket of a tile that may be in a row below the downwardly depending tongues; or if the tiles are reversed, so that the tongues are projected from the upper face of a row, then the sockets will be in the lower surface of the tier of the tiles above said projecting tongues, it being evident that it is immaterial as to position of the tongues and sockets so that the general construction is as stated, which will adapt the sockets to hold two tiles of an adjoining row above or below it interlocked, and thus bind the entire lining-wall of tiles from displacement when it is erected within the shell A. The sheet lead or asbestos joints are also introduced between each successive tier or row of tiles, and these joints are all preferably coated with a heat and acid proof composition, which will be further explained in proper order.

When the wall is erected within a digester-chamber, the material which forms the joints G is bent to conform to the shape of the tongues c and is coated with a plastic composition. I do not limit myself to any particular material for such coating, as there may be several compositions which will yield equally good results. I prefer to use a mixture of red lead or white lead and linseed-oil in suitable proportions to insure proper consistency as affording a plastic coating which will fill the interstices or slight inequalities in the surfaces of contact so as to form a solid joint, as heat will solidify such a plastic compound and render it hard as well as impervious to acid solutions.

The joints G between the tiles C may be calked or upset with a proper tool, so as to spread them laterally, this being effected where the joints are exposed on the circular face of the lining-wall.

At any suitable point on the tiles, either in front or to the rear of the tongue-and-groove connections c c', the body of the tiles are channeled, as at e, (see Fig. 2), said channels surrounding each tile, so that annular recesses are produced which mate and form a continuous ramification of grooves for the reception of asbestos joint material, which is made of such corresponding shape as to fit closely within the channels e and be therein embedded when the wall is erected. The asbestos joints e may also be coated with a plastic compound similar to that employed to cover the other joint material, as has been described, which, when spread properly upon the asbestos joint e, will close all crevices not filled by such material and thus render the joint e tight and acid-proof. It is of advantage, also, to coat the interior of the shell A with the plastic composition just named, as it will, if made of a semi-elastic material that expands under heat, protect measurably the shell from acid contact, and also prevent oxidation from water or steam contact. This is one of the features of my present invention.

The base B' of the lining C is preferably

made concave and provided at its center with an outlet O. The brick forming the base or bottom B' may be of any preferred form of construction, the outer row being made, preferably, of T shape to receive the bottom tier of bricks composing the side wall.

The bricks surrounding and forming the wall of the outlet or opening O are provided on their upper surfaces with a recess k, adapted to receive the flange k' of a lead, bronze, or other pipe P, capable of withstanding the effect of acid, which pipe extends through the opening O and may be provided with a valve of any preferred construction, said valve being preferably made of or covered with lead. If desired, thin sheets of asbestos k² may be inserted between the pipe P and its flange and the brick surrounding the opening O. A flange Q projects from the pipe P at a point a short distance below the bottom B'. This flange is provided with a series of screw-threaded perforations for the passage of a series of screw-threaded bolts l, which bear at their upper ends against the bottom plate of the shell A, and thus clamp the pipe P to its position.

It has been proposed to fasten the bricks or tile with bolts inserted in the shell, and also in the tile or the joints between them. Such a method of construction will not secure the brick or tile in place, as the expansion of the shell by heat and the elongation of the metal bolts from the same cause will permit the internal pressure of a steam-charge to injuriously affect the joints.

The annular space B, before referred to, may receive water under pressure slightly in excess of the internal pressure, so that the wall will be held intact, it being apparent that a superior counter-pressure applied to the outer face of the wall C will cause the joints to be compressed by the wedge shape of the brick or tile and their interlocking tongues, sockets, and grooves. Steam-pressure or compressed air, if introduced within the space B, will measurably support the lining-wall C; but water is preferred as an enveloping-jacket.

It will be noticed by inspection of Fig. 1 that the annular intervening space B is continued from the base of the digester above the arched wall of the lining C, and that in the upper portion of the digester-shell A the inlet and outlet pipes D D', respectively, are inserted through and affixed in the shell A to tap the space B, as shown. The pipe D is intended for the introduction of gaseous or liquid-filling fluid. The water entering through the pipe D, after circulating and heating, may be allowed to escape or be displaced by a constant inflow; or, if desired, any well-known means may be provided to allow the water to expand, by which the increased volume of water, occasioned by heat, will be provided for, so as to prevent a rupture of the shell A. If water is used, one or more water-gages I will be attached to the shell A, so as

to show if there is any leak or the acid solution into the water-space, for the leakage of the acid into the water-space will color the water, and its introduction into the glass tube of the water-gage I will at once give warning of the leak through the tile wall C.

The cooking of the wood chips or fragments within the digester-chamber is effected in the usual way by a perforated steam-coil R³, located at the bottom of the chamber, the steam entering said coil by a pipe R⁴, which is passed through the lining C in precisely the same manner as pipe P. As the steam-pressure employed for this purpose has a range of from sixty to one hundred and twenty pounds per square inch, it is evident that such a pressure would be liable to affect the integrity of the joints between the tile if they were not supported on the outer surface of the same, and for the purpose of preventing such a disaster the water-jacket above referred to is provided.

The shell A is provided with a removable cap-section that is flanged at R, said radial flange being adapted to seat on and be attached to a mating flange R', formed on the top edge of the cylindrical shell A by bolts or other secure means which will allow the cap-sections to be removed, if it is desired to do this, in order to clean out the intervening space B, renew or repair the wall C, or for other purposes.

I do not confine myself to a cylindrical shell for a digester, as a rectangular box might be used; but it is a better form for the purpose to employ a cylinder.

Other slight changes might be made, without departing from the spirit of my invention. Hence I do not wish to limit myself to the exact form shown; but,

Having fully described my invention, what I claim as new, and desire to secure by Letters Patent, is—

1. In a pulp-digester, the combination, with a shell, of tiles, each having a tongue projecting from one side, a groove at the opposite side, a socket on its upper face, and tongues on its lower face, the tongues of one tile being adapted to enter the corresponding grooves and sockets of the adjacent tiles, substantially as set forth.

2. In a pulp-digester, the combination of a shell and a lining separated from the shell so as to form an intermediate fluid-space, the said lining being composed of tiles, each tile having tongues adapted to enter sockets in the next adjacent tiles, and acid-proof filling located between the meeting faces of the tiles, substantially as set forth.

3. In a pulp-digester, the combination, with a shell, of a concentric lining composed of tiles, each tile having sockets, tongues, and a continuous groove, the latter being filled with an acid-proof material and located to register with the corresponding grooves in the adjacent tiles, substantially as set forth.

4. In a pulp-digester, the combination, with

a shell having a man-hole and cover, of a lining of glazed tiles, each tile having sockets and tongues, the tongues of one tile registering with the sockets in the adjacent tiles, and 5 acid-proof joint-plates shaped to correspond with the meeting faces of the tiles and located between said tiles, substantially as set forth.

5. In a pulp-digester, the combination, with a cylindrical shell, of a concentric wall or 10 lining of tile separated from the shell to form a fluid-chamber, said tiles being shaped to receive between them an acid-proof filling, 15 tongues and grooves formed on the tiles, sockets to receive tongues, and devices for inlet and outlet of water in the fluid-chamber between the shell and wall, substantially as set forth.

6. In a pulp-digester, the combination, with a cylindrical shell, inlet and outlet valves in 20 said shell, a man-hole, and a detachable cover for the man-hole, of a concentric tile wall, each tile having tongues, sockets, and grooves, substantially as described, and acid-proof joints introduced between the shell and lining 25 wall of tiles, substantially as set forth.

7. In a pulp-digester, the combination, with a cylindrical shell, a man-hole, a cover, and means for securing the cover, of a concentric wall of glazed tiles, tongues, and mating 30 grooves and sockets formed on and in these tiles, plate-lead joints placed between the adjacent faces of the tile, and a plastic heat and acid proof coating for the lead joint material, substantially as set forth.

8. In a pulp-digester, the combination, with 35 a cylindrical shell, a concentric wall of glazed tile, each tile having an annular channel formed in it, and a tongue, socket, and grooved interlocked joint between the tile, of acid-proof filling between the tile and in the annular 40 grooves and a plastic composition which is acid and heat proof and is applied to the joint material, between the tile, substantially as set forth.

9. In a pulp-digester, the combination, with 45 a metal shell lined with acid, heat, and water proof material, of an inner lining of glazed tiles, each having tongues and sockets, the 50 tongues of each tile registering with the sockets of the adjacent tiles, and acid-proof filling between the meeting faces of the tiles, substantially as set forth.

10. In a pulp-digester, the combination, with a metal shell, of an interior tile wall located so as to produce an annular space between it and the shell, and a film or thin 55 coating of heat, acid, and water-proof material applied to the interior surface of the shell, substantially as set forth.

In testimony whereof I have signed this 60 specification in the presence of two subscribing witnesses.

ELI A. D. REYNOLDS.
